FIRE EXTINGUISHER

Charles H. Barnes, Washington, D. C.

Application August 8, 1944, Serial No. 548,592.

19 Claims. (Cl. 169—31)

(Granted under the act of March 3, 1883, as amended April 30, 1928; 370 O. G. 757)

1

This invention relates to hand fire extinguishers and more particularly to chemical fire extinguishers of the dry powder type using a compressed gas to entrain and discharge the powder in the form of a stream of dust.

It is desirable that fire extinguishers of the type here considered be capable of discharging powder in any position in which they may be held. Heretofore, there was no certainty that the powder entraining means would be in a position to pick up the powder for any position in which the extinguisher may be held. When held in a horizontal position the pickup means may or may not be in the powder supply and if held vertically the gas will by-pass the entraining means causing the powder to pack and lose its fluid-like properties. In either event, satisfactory operation of the extinguisher is a matter of chance and any erratic operation would require a knowledge of the cause thereof in order that it may be manually manipulated in a manner to cause it to operate.

Thus the primary problem involved in producing a constant uniform discharge of powder is that of entraining the powder in the gas stream used to discharge the same. Such discharge will not be obtained, nor the available supply of powder be completely used, unless some means are provided for keeping the powder in the extinguisher always accessible to the entraining means and limiting operation of the entraining means to that portion of the extinguisher containing powder.

The object of this invention is to provide a fire extinguisher operable in any position to discharge the contents thereof.

A further object of this invention is to provide a fire extinguisher with means for feeding the extinguishing agent to the discharge means in any position of the extinguisher.

A further object of this invention is to provide a fire extinguisher having all openings sealed when not in use.

A further object of this invention is to provide a fire extinguisher whose air inlet and discharge nozzle are opened or closed by a single operation.

A further object of the invention is to provide a fire extinguisher in which the means for entraining the extinguishing agent is always maintained in the same position.

A further object of this invention is to provide a fire extinguisher in which the extinguishing agent container is held in operable position by gravity.

A further object of the invention is to provide

means for unseating the discharge nozzle of a fire extinguisher during the turning thereof.

Other objects of the invention will be more fully disclosed in the following specification and 5 claims.

According to the invention the fire extinguisher comprises an elongated casing, adapted to be grasped with one hand, in which is rotatably mounted a closed cylindrical container for the extinguishing agent. This container is so weighted that one side thereof is always lowermost. This container also carries the means for creating air pressure therein for expelling the extinguishing agent. The means disclosed is a manually 10 actuated pump, though other devices, as for example a cylinder of compressed gas, may be substituted therefor. The compressed gas is fed into a valve chamber having two gravity operated check valves therein whereby tilting of the extinguisher will cause one or the other of the valves to close. These valves control the flow of gas into two tubes coupled to the valve chamber at opposite ends thereof. These tubes run along the bottom of the chamber to the ends thereof farthest 15 removed from the point of attachment of the tube to the chamber and are provided with openings along the length thereof. This arrangement of tubes and gravity operated valves serves to direct the gas into the tube in the lower end of the extinguisher when the latter is directed up or down thereby always causing the gas to flow through that portion of the entraining means immersed in powder which gravitates to the lower end. The two tubes discharge into a nozzle which has a 20 port for alignment therewith. This nozzle is releasably connected to the handle of the pump so that when the latter is unlatched for operation, it turns the nozzle port into alignment with the tubes. The air inlet for the pump is covered by 25 the handle when closed and unlatching the handle opens the air inlet. As the center of gravity of the container is below the axis thereof, it always assumes the same position regardless of the angular displacement of the casing. As the extinguishing agent gravitates to the lowermost side, the tubes are supplied with powder as long 30 as any thereof remains in the container.

Fig. 1 is a longitudinal sectional view of the fire extinguisher, with the pump handle in latched position; Fig. 2 is an enlarged fragmentary sectional view of one end of the extinguisher with the handle unlatched; Fig. 3 is an end view thereof; Fig. 4 is a cross sectional view of the flange along the line 4—4 of Fig. 3 showing the handle 35 latching groove; Fig. 5 is a cross sectional view,

on the line 5—5 of Fig. 1; Fig. 6 is an enlarged fragmentary sectional view of the nozzle end of the extinguisher showing the nozzle actuating means; Fig. 7 is a cross sectional view along the line 7—7 of Fig. 6; Fig. 8 is a slightly enlarged plan view of the powder entraining means taken along the line 8—8 of Fig. 1; Fig. 9 is a detail of the powder entraining means; Fig. 10 is a detailed longitudinal sectional view of the piston; Fig. 11 is a longitudinal sectional view of the nozzle end of the extinguisher showing the clutch and nozzle when the handle is locked in the position shown in Fig. 1; Fig. 12 is a longitudinal sectional view showing the nozzle unseated during the locking of the handle; Fig. 13 is an end view of the clutch plate affixed to the piston rod.

Referring more particularly to the drawings, Fig. 1 shows the extinguisher as comprising an elongated cylindrical casing 10 of some suitable material, such as sheet metal, one end of which is provided with an end wall 11 integral therewith. The other end of the casing is open and is adapted to be closed by a cover 12 which is affixed thereto by screw threads 13. Within the casing 10 is an elongated cylindrical container 14 of sheet metal, or like material, and of slightly smaller size, which carries the extinguishing agent such as, for example, a fine powder. The container 14 is rotatably mounted in the casing 10 so that either one thereof freely rotates with respect to the other. The axes of the casing and container coincide and the bearing means, subsequently described, are at either end. The means for generating gas pressure is carried within the container 14 and comprises an air pump 15 axially aligned therewith and rigidly attached thereto.

The air pump 15 is of the double action type and, as shown in Figs. 2 and 6, comprises a cylinder 16 provided with valve chambers 17 and 18 at either end thereof. The outer end of the valve chamber 18 is provided with a shoulder which abuts the apertured end of the container 14 and is affixed thereto by ring 20 threaded on the reduced portion of the valve chamber projecting through the end wall. The valve chamber 17 has attached thereto, by means of arms 67, a nozzle casing 68 clamped centrally of the end wall of the container 14 by means of a shoulder 21 formed thereon and a ring 19 threaded on a reduced portion of the valve casing projecting through the end wall. The outer end of the valve casing 68 carries a felt washer 69 and a plastic disc 70 which are journaled on a bearing 71 fastened to the center of the apertured end wall 11 of the casing 10.

Chamber 18 is provided with an air inlet port 23, an inlet valve 24 and an outlet valve 25. Chamber 17 is similarly provided with an air inlet valve 26 and an air outlet valve 27. The air inlet valve 26 is supplied with air by means of pipe 28 connected to the valve chamber 17 at one end and to the air intake 23 at the other. The inlet and outlet valves are of conventional type, comprising a valve head 29 affixed to a valve stem 30 which passes through the apertured insert 31. The valve is urged to closed position by means of a light coil spring 32. A piston 33 attached to piston rod 34 operates in cylinder 16. The piston is loosely mounted on the piston rod, permitting free rotation thereupon. Fig. 10 shows the means whereby this is accomplished. A fitting 35 carried on the end of the piston rod 34 is provided with a central portion 36 of reduced diameter. A boss 37 integral therewith is provided with a slop-

ing face 38. A cap 39 screwed on the other end of the fitting has a sloping face 40 formed thereon. Cotter pins 41 and 42 prevent rotation between the several parts. The piston is provided with a central aperture 43 of a size permitting a loose fit on the reduced portion 36 of the fitting 35. The opposite faces of the piston have conical recesses 44 and 45 formed therein, the slope of which is the same as that of faces 38 and 40 of the boss 37 and cap 39 which seat therein. The spacing between the face of the recess 44 and 45 is slightly less than that between the faces 38 and 40 permitting axial play between the piston and the fitting. Piston rings 46 of some suitable material, such as felt, are carried in a suitable groove formed in the outer periphery of the piston. Movement of the piston rod 34 in either direction will cause the boss or the cap on the fitting to seat in one of the recesses in the piston sealing the same from leakage of air compressed thereby through the piston at this point through the limit of movement thereof yet permitting free rotation of the piston with respect to the rod for reasons subsequently to appear.

The piston rod 34 passes through a central aperture 47 in the valve chamber 18 which also carries the means for journaling one end of the container for rotation about the piston rod 34 with a minimum of friction. An annular flange 48 on the valve chamber carries two plastic washers 49 and 50 separated by a felt washer 51 which acts as an air seal and lubricant carrier. These journaling elements are retained in the flange by turning the edge thereof over the outer disc 50.

The piston rod 34 extends through a centrally located opening 52 in the cover 12 and carries a handle 53 at the outer end thereof. In order that the handle 53 may be latched to the cover 12, the latter is provided with an upstanding flange 54 symmetrically spaced with respect to the opening 52. This flange 54 has a recess 55 in the inner wall thereof, Fig. 4, and an under cut groove 56 communicating with the lower end of the recess 55 and extending through 90° of the circumference of the flange, terminating in a depression or seat 57 formed in the outer side of the groove 56. The handle is enlarged at its point of attachment to the piston rod 34 so that it loosely fits within the flange 54 and carries a protruding lug 58 (see Figure 1) adapted to pass through the recess 55 by movement thereof in an axial direction to the groove 56 where it may be manually turned until it seats in the depression 57. This construction permits the handle to be locked in only one position with respect to the cover. The cover 12 has several air inlet openings 59 located around the opening 52 to admit air to the pump. A gasket 60 of some resilient material is affixed to the handle 53 and serves to seal the openings 59 when the handle is locked. A filter 61 is held against the inner side of the cover adjacent the openings 59 by means of a spring 62. The spring 62 is housed in an annular flange 63 and bears against a centrally apertured cap 64 threaded into said flange. The end of this cap abuts the washer 50 and serves to axially space the container 14 the proper distance from the cover 12. The flange 63 is provided with a series of circumferentially spaced openings 65 to permit passage of air to the pump.

The container 14 has a funnel shaped fitting 107 fixed in one end thereof in which a screw plug 109 is adapted to be screwed. A threaded plug 75 109 in the cover 12 provides access to the fitting

107 by means of which the container may be filled with powder.

From the foregoing description it will be seen that the container 14 is free to rotate about the piston rod 34 at one end and about the bearing 71 at the other end. By reason of the friction between the piston rings 46 and the cylinder 16 the piston rotates with the cylinder. However the loose mounting of the piston 33 on the piston rod permits the piston to rotate with respect to the rod thus enabling the container 14, when properly counterbalanced to maintain a constant position with respect to the earth regardless of any turning of the casing 10 about its axis. That is to say, with the container properly weighted, rotation of the casing 10 about its longitudinal axis will not cause rotation of the container 14 whose weighted side is maintained lowermost.

Air compressed by the pump 15 through manual operation of the piston is conducted to a cylindrical valve chamber 72, located in the container 14 below the pump 15, by means of pipes 73 and 74. From the chamber 72 the air is fed to the slightly flattened powder pickup tubes 75 and 76 which are located in the bottom of the container 14. The tubes carry means 78 for feeding powder thereto which, as shown in Fig. 9, comprise funnel shaped members attached to an elbow fitting 80 whose free end projects into the tubes so that its outlet end is axially aligned with the tube whereby air passing the elbow will draw powder thereinto. Tube 75 has powder inlets along only that portion thereof located in one end of the container 14 or on one side of the chamber 72. Air for this tube is supplied from the other side of the chamber. Tube 76 is provided with powder pickup means 78 in the other end of the container and is connected to that end of the chamber 72 opposite the connection for tube 75. By this arrangement each tube picks up powder from only one end of the container.

Valve chamber 72 houses two gravity actuated check valves 81 and 82 which control the flow of air from the chamber into tubes 75 and 76 connected thereto. Each valve comprises a ball 83 closely held in a cage guide 84 attached to a valve seat screwed into an opening in the end of the chamber to which the pipe 75, or 76, is connected. The lower side of the cage guide 84 is inclined downwardly away from the valve seat to which it is attached. When the extinguisher is held horizontally the check valves are open and air flows into both tubes, but if tilted, one of the check valves closes preventing flow of air in the tube at the upper end of the extinguisher.

The tubes 75 and 76 merge as shown in Fig. 7 and connect with a port 85 in the nozzle casing 68. A conical nozzle 86 for discharging the powder is rotatably mounted in a conical nozzle seat in the nozzle casing 68. A port 87 in the nozzle, connecting with a central aperture 88, is adapted to register with the port 85 to permit discharge of powder therefrom. Rotation of the nozzle 90° from the position shown in Figs. 6 and 7 will serve to cut off the flow of powder. A stop 90 projects into a groove 93 cut in the periphery of the nozzle to limit the rotation thereof to 90°. The slot 90 is of a width permitting axial movement of the nozzle with respect to the stop 93.

The chamber 72 and the tubes 75 and 76 ordinarily will be sufficient to counterbalance the container to maintain it in one position, but an additional weight (not shown) may be added to the lower part thereof to increase the counterbalancing effect.

The opening and closing of the nozzle 86 is under the control of the pump handle 53 so that unlatching the pump handle will turn the nozzle to align the ports in the nozzle and the nozzle casing and latching the handle in closed position will disalign them. The cap 39 of the fitting 35 attached to the piston rod 34 is provided with an axially directed stem 91, Fig. 10, having key ways 92 formed therein. Mounted on the stem 91 for sliding movement in an axial direction is a centrally apertured clutch plate 93 having keys 94 formed integral therewith and projecting into the central aperture to engage the keyways 92 to prevent rotation of the clutch plate 93 with respect to the stem 91 while permitting axial movement thereon. A washer 95 screwed to the end of the stem retains the clutch plate on the stem and a spring 96 urges the clutch plate against the said washer 95. The clutch plate 93 is provided with an annular row of teeth 97 around the periphery thereof. A second clutch plate 98 formed similar to the other is coupled to the nozzle 86 by means of a shaft 99 which passes through a centrally located aperture 102 in the valve chamber 72. The head of the screw affixing washer 95 is adapted to abut the clutch plate 98 when the clutch is engaged. A spring 100 bearing on the nozzle casing 68 and a washer 101 fastened to the shaft serves to urge the nozzle into contact with its seat. The shaft 99 is journaled in the valve chamber 72 by means of two plastic discs 103 and 104 spaced by a felt washer 105 all of which are retained by an annular flange 106. The felt washer 105 serves as an air seal and prevents leakage of air, compressed by the pump, around the shaft. This clutch when engaged furnishes a direct connection between the nozzle and the handle whereby manipulation of the latter will operate the nozzle to open or closed position.

When not in use the fire extinguisher has the handle 53 thereof in locked position as shown in Fig. 1 wherein the lug 58 is seated in the depression 57 in the groove 56. The gasket 60, attached to the handle, seals the air inlet openings 59. The clutch is in engagement as shown in Fig. 11 and the nozzle is turned so that the ports 85 and 87 of the nozzle casing and nozzle, respectively, are not aligned. The container is therefore sealed and prevents the admission of air and moisture which may have a deleterious effect on the powder. The container 14 will be counterbalanced to a position such that the powder pickup tubes 75 and 76 are at the bottom thereof.

To unlatch the handle 53, it is first pushed axially a slight distance to disengage lug 58 from the depression 57 and then turned 90° to permit the lug to pass through the recess 55 in the flange 54. As the clutch plates 93 and 98 are engaged when the handle is latched and for the duration of the turning movement, any movement of the handle causes movement of the nozzle 86 by means of the connection therebetween, namely the piston rod 34, clutch, and shaft 99. The small initial axial movement of the handle is transmitted through the abutting members of the clutch assembly to the nozzle 86 which causes it to be pushed from its seat against the retaining force exerted by spring 100 as shown in Fig. 12. This feature is provided to prevent any sticking of the nozzle in the seat as may be occasioned by the nonuse of the extinguisher for long periods of time, or corrosion of the parts. The turning of the handle until the lug reaches recess 55 turns 75 the nozzle 86 to a position where the port 87

thereof aligns with the port 85 of the nozzle casing 68. As the lug passes through the recess 55 and clears the flange 54, the nozzle first reseats and then the clutch disengages to the position shown in Fig. 6. The air inlet openings 59 are uncovered by this unlatching movement. The pump is then operated by imparting a reciprocating motion to the piston. Movement to the left will cause valve 26 to open and let the piston draw air from the inlet port 23 through pipe 28. Air is compressed on the other side of the piston, opening valve 25 forcing air through pipe 73 into the chamber 72 from where it flows into the pickup tube 75 and 76 entraining powder fed therein by the means 78. This mixture of air and powder is discharged through the nozzle 86 to which the tubes are connected. Movement of the piston in the opposite direction causes a similar operation with respect to valve 27 and pipe 74.

If the extinguisher is tilted, the appropriate check valve in the bell cuts off the flow of air into the uppermost pickup tube thus forcing all of the air through that tube to which the powder gravitates, a material consideration when the container becomes less than half full.

In latching the handle closed the reverse of the opening procedure is observed, the clutch is first engaged, the nozzle unseated and turned to closed position and then reseated. The spring 96 and clutch plate 93, keyed for axial movement on the stem 91, prevent damage to the clutch in the event the teeth thereon do not exactly mesh when they first make contact or permit the clutch plates to slip if the nozzle becomes jammed, to avoid damage to the extinguisher.

While I have described the preferred form of my invention I do not wish to limit myself to the precise details shown but wish to avail myself of such variations and modifications as may come within the scope of the appended claims.

The invention described herein may be manufactured and used by or for the Government of the United States of America for governmental purposes without the payment of any royalties thereon or therefor.

I claim:

1. A fire extinguisher comprising a casing adapted to be held in the hand, a container for an extinguishing agent, means journaling said container in said casing to permit relative rotation therebetween, means fixed to said container for entraining the extinguishing agent and counterbalancing said container to one position and means fixed to said container for rotation therewith for supplying gas under pressure to said entraining means.

2. A fire extinguisher comprising a casing, a container adapted to hold an extinguishing agent, means journaling said container in said casing, pressure generating means affixed to and in said container for rotation therewith, a pickup means counterbalancing said container to one position and connected at one end to said pressure generating means, and nozzle means carried by said container and connected to the other end of said pickup means.

3. A fire extinguisher comprising a casing, a container adapted to carry an extinguishing agent, means journaling said container in said casing, pickup means affixed to one side of said container, said pickup means counterbalancing said container to keep said side lowermost, gas pressure means carried by said container for rotation therewith and connected to said pickup means and a discharge means carried by said con-

tainer connected to said pickup means and discharging through said casing.

4. A fire extinguisher comprising a casing, a container in said casing, means journaling said container in said casing, pressure generating means in said container, discharge means carried by said container, pickup means counterbalancing said container to one position and connecting said pressure means and discharge means said container, pressure generating means and pickup means rotating as a unit in said casing.

5. A fire extinguisher of the dry powder type comprising a cylindrical powder container, a casing therefor, means journaling said container in said casing for free rotation therein, a source of compressed air affixed to said container and rotatable therewith, apertured tubes along one side of said container counterbalancing said container to maintain said tubes at the lowermost point therein, means connecting said source of compressed air and said tubes, discharge means carried by said container and connected to said tubes.

6. A fire extinguisher as claimed in claim 5, said connecting means comprising a valve chamber and gravity operated check valves in said chamber controlling the flow of air to said tubes.

7. A fire extinguisher of the dry powder type comprising an elongated casing, a cylindrical container for the powder, means journaling said container for rotation about the axis thereof in said casing, an air pump mounted axially of said container, a piston rod for said pump projecting from said container and casing, a valve chamber in said container connected to said pump, perforated tubes connected to said chamber to receive air therefrom, gravity operated check valves in said chamber controlling the flow of air to said tubes, said tubes discharging through the end of said container.

8. In a fire extinguisher, a casing, a container journaled in said casing, discharge means, said means comprising a pump and a cutoff nozzle, said pump having a piston and a piston rod, means for locking said rod to said casing and clutch means carried by said nozzle and said rod engageable during locking of said rod to close said nozzle.

9. In a fire extinguisher of the dry powder type 50 a casing, a container journaled in said casing, powder ejecting means in said casing, said means comprising an air pump and a cutoff nozzle, said air pump having actuating means extending through one end of said casing, an air inlet adjacent said actuating means and means carried by said actuating means for simultaneously controlling said air inlet and said cutoff nozzle.

10. In a fire extinguisher a casing, a container journaled in said casing, apertures in one end of 60 said casing, an air pump in said casing having a piston and piston rod, said rod extending through one end of said casing adjacent said apertures, means locking said rod to said casing, means carried by said rod closing said apertures when said rod is locked, a cutoff nozzle carried by said container, means connecting said rod and said nozzle during locking of said rod to unseat and cut off said nozzle.

11. In a fire extinguisher of the dry powder type, a casing, powder ejecting means in said casing, said means including an air pump and a cutoff nozzle, said air pump having a piston rod projecting from said casing, an air inlet in said casing adjacent said rod, means carried by said 70 rod to close said inlet when said rod is at one ex-

treme position and means coupling said nozzle and said rod in said extreme position whereby the said air inlet and said nozzle may be opened simultaneously by manipulation of the said rod.

12. In a fire extinguisher, a casing, a container journaled in said casing, a pump in said container having a piston and a piston rod, said rod projecting from said casing and container, means locking said rod to said casing, discharge means connected to said pump comprising a cutoff nozzle, means coupling said nozzle and rod when said rod is in locked position whereby unlocking said rod opens said cutoff nozzle.

13. In a fire extinguisher, a casing, a container in said casing, a pump in said casing a piston rod projecting from said casing, a lug on said rod, a flange external of said casing, a recess in said flange to receive said lug through axial movement, an undercut groove in said flange to permit angular movement of said lug and a depressed seat in said groove to latch said lug, a cutoff nozzle, means coupling said rod and nozzle during axial movement of said lug in said recess to unseat said nozzle and rotating said nozzle during angular movement of said lug in said groove and reseating said nozzle when said lug rests in said depressed seat.

14. In a fire extinguisher of the dry powder type, a casing, a powder container journaled in said casing, a source of compressed gas in said container, means counterbalancing said container to maintain one side thereof lowermost, said means comprising a valve chamber and a pair of pickup tubes connected to the ends of said chamber, each of said tubes extending to the end of the container opposite from the point of connection with the said chamber, apertures in said tubes in the portion thereof remote from the point of connection with the said chamber, gravity operated check valves in said chamber for controlling the flow of air to the tubes, whereby tilting of the extinguisher will cause the check valve controlling the flow of air to the uppermost tube to close.

15. In a fire extinguisher of the dry powder type, a casing, a powder container, means journaling said container in said casing, an air pump in said container, means counterbalancing said container to maintain one side thereof lowermost, said means comprising a valve chamber and a pair of pickup tubes, said tubes connected one to each end of said chamber and each extending into an end of said container opposite the end of the valve chamber where connected, apertures in said tubes in the portion thereof remote from the point of connection with said chamber for admitting powder to said tubes, gravity operated check valves in said chamber controlling the flow of air to said tubes, means connecting said pump to said chamber, and means connected to said tubes for discharging powder from said container.

16. In a fire extinguisher, a casing, a powder container in said casing, means journaling said container in said casing, a pump mounted axially in said container, said pump comprising a piston and a piston rod, said rod projecting from said container and said casing, means locking said rod to said casing in one position, powder entraining means in said container, a cutoff nozzle carried

by said container for discharging powder therefrom, said nozzle being rotatably mounted in a nozzle casing affixed to said container, clutch means affixed to said piston and said nozzle whereby locking of said handle cuts off said nozzle.

17. In a fire extinguisher, a casing, a container adapted to receive an extinguishing agent, means journaling said container in said casing, agent entraining means counterbalancing said container to maintain said means lowermost in said container, an air pump axially positioned in said container and connected to said entraining means, said pump having a piston and a piston rod, said rod projecting from said container and casing, a handle affixed to said rod, means locking said handle to said casing in one position, discharge means connected to said entraining means, said discharge means comprising a nozzle casing carried by said container, a nozzle rotatably seated therein, ports in said nozzle and nozzle casing, clutch means carried by said piston and said nozzle engageable during the locking of said handle to disalign said ports.

18. In a fire extinguisher of the dry powder type, ejecting means comprising means for producing gas under pressure, powder entraining means connected to said pressure means, said entraining means comprising a tube and means directing powder into said tube in the direction of gas flow in said tube whereby gas flow in said tube past said last mentioned means will draw powder into said tube.

19. In a device of the character described, an enclosure, a substantially cylindrical powder container rotatably mounted in said enclosure for rotation about the axis of the container, an air pump cylinder arranged axially within the container and spaced from the wall thereof to provide a chamber for the powder, means for admitting air into each end portion of the cylinder, a reciprocatory piston arranged in the cylinder, a piston rod connected to the piston and extending through an end of the container to the exterior of the enclosure, an outlet for air and entrained powder arranged at the opposite end of the container, conduit means extending through said chamber and placing the end portions of the pump cylinder in communication with said outlet, means arranged along the conduit means for admitting powder from said chamber into the conduit means, and gravity operated valve means interposed in the conduit means for controlling the flow of air therethrough.
